UNITED STATES PATENT OFFICE.

WALTER H. MILLER, OF LEBANON, PENNSYLVANIA, ASSIGNOR TO BETHLEHEM STEEL COMPANY, OF BETHLEHEM, PENNSYLVANIA.

OIL BURNER.

Application filed September 16, 1921. Serial No. 501,029.

To all whom it may concern:

Be it known that I, WALTER H. MILLER, a citizen of the United States, a resident of Lebanon, county of Lebanon, and State of Pennsylvania, have invented certain new and useful Improvements in Oil Burners, of which the following is a specification.

This invention relates to liquid fuel burners for heating purposes, and is particularly adapted for burning tar. It includes a steam or compressed air ejector so arranged that it will, by its suction or the partial vacuum created by it, draw the tar at the desired rate for burning from a source of supply, thus avoiding the necessity for maintaining the tar under pressure and the incident expense for mechanism for producing and maintaining such pressure. It includes means for atomizing the ejected oil mixed with air or steam, solely through the action of a circular jet of steam or air as distinguished from a mechanical atomizer, and it supplies air in considerable volume under some pressure to the atomized mixture to support combustion. The passage ways for the liquid fuel and gaseous fluid throughout the burner through and including the discharge end have no valves, contracted portions or any stationary physical thing interposed in the path of travel of the fluid, and thus the flow is free and unobstructed throughout. The device is of such simple construction that it may be made in the field by ordinary mechanics from standard pipes, pipe couplings and bushings, without machining or other work except connecting the parts together in proper relations by screw threaded joints. The supplies of liquid fuel and gaseous fluid are regulated solely by valves in the gaseous fluid supply pipes, and it has been found in practice that this simple device is capable of such regulation as to insure complete combustion of tar delivered to it, without the aid of gaseous fuel as has been found necessary with most other types of tar burners. The novel features will be more fully understood from the following description and claims taken with the drawings.

50 In the drawings:

Figure 1 is a longitudinal section through the burner proper, and

Figure 2 is a side view of the burner with its pipe connections.

55 In the embodiment of the invention shown

in the drawings, the small, inner pipe 10 is connected to a source of steam pressure through the pipe 11 or to a source of compressed air by pipe 12, and it will be seen it passes through the aligned openings in 60 the pipe couplings 13 being held in place by the gasket 14 having screw threaded connection with one of the openings in the coupling 13, and its discharge end projects some distance from the opposite side of the coupling. A pipe 15 is connected to the third side opening 16 of the coupling 13 and supplies a liquid fuel and has a branch pipe 17 connected to a supply of tar which is preferably heated so as to render it sufficiently fluid to be drawn up into the burner. The pipe 15 is also connected by a branch 65 18 to a source of oil supply for use in starting the operation of the burner before opening the connection for the supply of tar. A pipe 19 has screw threaded engagement at one end in the opening in the coupling 13 around pipe 10 and is concentric therewith and extends materially beyond the end of 70 pipe 10. A pipe coupling 20 surrounds the pipe 19 near the coupling 13 and the pipe 19 passes through the bushing 21 in one of the aligned openings of the coupling 20 and is thereby connected to the coupling. A pipe 22 for compressed air or steam is connected to the third opening 23 of the coupling 20 and has valve controlled branches 24 and 25 adapted to be connected respectively to a container for compressed air and a source of steam. A pipe 26 is secured 75 at one end in the opening in the coupling 20 around the pipe 19 and projects therefrom around and concentric to the pipe 19 to approximately its discharge end. Preferably the pipe 26 terminates a little short 80 of the end of the pipe 19. A pipe coupling 27 surrounds the two pipes 19 and 26 which pass centrally through its two aligned openings and are held in place by the bushing 28 85 engaging the outer pipe 26 and one of the openings in the coupling. A pipe 29 is secured at one end in the opening in the coupling 27 around the ends of the pipes 19 and 26 and projects some distance beyond their ends. It will be noted that this coupling 27 90 and pipe 29 have an interior diameter materially greater than that of the pipes 19 and 26, thus leaving a comparatively large open space around them for the passage of air under some pressure to support combus- 95 100 105 110

tion. The air may be forced in through a pipe 30 by a fan or other suitable means.

In operation the jet of compressed air or steam discharged by pipe 10 into the pipe 19 will, because of the small circular space around it and the length of the pipe 19 beyond the discharge, act as an ejector creating a partial vacuum behind the point of discharge thus drawing the tar from the 10 source of supply through the pipe 15 without the necessity of applying pressure to the tar supply. The tar and steam or air will be more or less intimately mixed during their passage through the pipe 19 and at the 15 discharge end of that pipe the circular jet of compressed air or steam from the pipe 23 will serve to thoroughly atomize the mixture and the air supplied through pipe 30 around the discharge end of said pipe will be distributed throughout the atomized mixture 20 and support combustion. As shown, suitable valves are used to regulate and control the supply of the gaseous fluid in the form of steam or compressed air and the supply 25 of liquid fuel is regulated, indirectly, by these valves. The fan blast through pipe 30 may also be controlled by an ordinary valve mechanism.

Having thus described my invention what 30 is claimed as new and desired to be secured by Letters Patent is:

1. In a liquid fuel burner, the combination of a mixing tube connected to a source 35 of fuel supply, means providing a jet of motive fluid in the mixing tube for the entrainment of fuel, for admixture with the latter, and for the translation of the resultant mixture, a second mixing tube coaxial with the first mixing tube, of materially larger diameter than the latter and having the discharge end portion of the first mixing tube arranged therein, means providing an annular jet of motive fluid between the tubes for atomizing the mixture 40 discharged from the first tube, means for passing a forced-draft stream of air about the last-named means for admixture with the atomized mixture, and means for regulating the flow of air through the last-named 45 means to secure proper admixture of such air with the atomized mixture issuing from the first mixing tube.

2. The combination with an ejector for 55 entraining liquid fuel by a jet of high-velocity motive fluid and including a mixing tube for the discharge of the resultant mixture of motive fluid and fuel, of a second mixing tube of materially larger diameter than the first mixing tube and overlapping the discharge end of the latter, a tube member 60 surrounding the first mixing tube, having its discharge end arranged between the mixing tubes, and being connected to a source of fluid under pressure to provide for 65 an annular jet of motive fluid to atomize

the mixture discharged from the first mixing tube, means for supplying a forced-draft stream of air to the second mixing tube at a point back of the annular jet, and means for regulating the flow of air through 70 the last-named means to secure proper admixture thereof with the atomized mixture issuing from the first mixing tube, at a point back of the annular jet.

3. In a liquid fuel burner, the combination 75 of a mixing tube connected to a source of fuel supply, means providing a jet of motive fluid in the mixing tube for the entrainment of fuel, for admixture with the latter, and for translation of the resultant 80 mixture, a second mixing tube coaxial with the first mixing tube, of materially larger diameter than the latter and having its inlet end portion overlapping the discharge end portion of the first mixing tube, an air supply chamber surrounding the first mixing tube and in open communication with the inlet end of the second mixing tube, a motive fluid supply tube telescopically arranged with respect to the first mixing tube, traversing 85 said air chamber, and terminating within the inlet end of the second mixing tube to provide, with respect to the first mixing tube, an annular jet discharging into the 90 second mixing tube.

4. In a liquid fuel burner, the combination 95 of a first mixing tube of uniform diameter, a second mixing tube of uniform but of larger diameter than the first tube, the discharge end portion of the first tube being disposed within the inlet end portion of the second tube, a first motive fluid tube for supplying a jet of motive fluid axially of and within the first tube, means for supplying fuel to the first tube rearwardly of the 100 discharge end of the first motive fluid tube, a second motive fluid tube surrounding the first mixing tube and having its discharge end arranged between the inlet end of the second mixing tube and the discharge end 105 of the first mixing tube, an air supply chamber surrounding the second motive fluid tube and in open communication with the second mixing tube.

5. In a liquid fuel burner, the combination 110 of a first mixing tube of uniform diameter, a second mixing tube of uniform but larger diameter than the first tube, the discharge end portion of the first tube being disposed within the inlet end portion of the second tube, a first T-coupling having one arm connected to the inlet end of the first mixing tube, a first motive fluid supply tube connected to and passing through the opposed arm of the coupling and terminating 115 within and rearwardly of the inlet end of the first mixing tube, liquid fuel supply means connected to the third arm of the coupling, a second T-coupling surrounding 120 and having one arm connected to the first 125

mixing tube, a second motive fluid tube connected to the opposed arm of the second coupling and telescopically arranged with respect to the first mixing tube, means for 5 supplying motive fluid to the third arm of the second coupling, a third coupling surrounding the telescoping first mixing and second motive fluid tubes and having one arm connected to the second motive fluid tube and having its opposed arm connected to the second mixing tube, and means for 10 supplying air to the third arm of the third coupling.

6. A burner construction of the type described comprising, in combination, an inner pipe for gaseous fluid under high pressure having a substantially uniform inner diameter to and including its discharge end, a 15 concentric unobstructed tube of uniform diameter surrounding the discharge end of said first mentioned tube and extending a material distance beyond that discharge end; means connecting said last mentioned tube at the rear of the discharge end of said 20 first tube to a source of supply of liquid fuel, the relative sizes of said tubes being such that they will act as an ejector creating a partial vacuum in the rear of the inner pipe discharge thus drawing in the liquid 25 fuel, and means at the outlet end of said second mentioned tube for subjecting the escaping mixture of liquid fuel and gaseous fluid to a surrounding jet of gaseous fluid 30 to atomize it, and an enlarged tube of uniform diameter for air under pressure surrounding said outlet end where the atomizing takes place and extending a material 35 distance beyond that point.

7. A burner construction of the type described comprising in combination a series 40 of concentrically arranged pipes each being of substantially uniform interior diameter throughout including its discharge end, the innermost pipe entering the next outer pipe 45 at its inner end for a short distance and discharging therein, means for forcing gaseous fluid under pressure through said innermost pipe into said next outer pipe, producing suction by ejector action, means connecting 50 said next outer pipe to a source of supply of liquid fuel whereby said fuel will be drawn into said pipe solely by the suction produced by the ejector action of the gaseous fluid, the next outer pipe around the last 55 mentioned pipe terminating at approximately the outlet end of said last mentioned pipe, and means for passing gaseous fluid through said last mentioned pipe which in escaping sprays the escaping mixture of liquid fuel 60 and gaseous fluid, and an enlarged outer pipe for supplying air under pressure to aid in supporting combustion.

8. A tar burner comprising in combination 65 a series of concentrically arranged spaced pipes each being of uniform diameter

throughout including its discharge end, the inner and smallest pipe of the series for steam or compressed air entering the end of the next outer pipe in the series for liquid fuel for only a small portion of its length 70 at its inlet end, the next outer pipe for compressed air or steam surrounding said fuel pipe from approximately its discharge end to a point near its inlet end and spaced therefrom only a short distance and the 75 outermost pipe of the series for a blast of air surrounding and extending beyond the discharge ends of said last two mentioned pipes and being spaced laterally therefrom a material distance sufficient to furnish a 80 large proportion of the air necessary to support combustion.

9. A burner of the type described comprising in combination, a pipe coupling having a pipe secured at one end in one of its 85 two aligned openings and extending a material distance therefrom, a bushing in the opposite opening of said coupling, a pipe having a diameter less than that of the first pipe extending through said bushing 90 concentrically into the end of said first pipe, an inlet pipe for liquid fuel connected to the third side opening of said coupling, a second larger pipe coupling having a pipe secured in and projecting from one of its aligned 95 openings and a bushing in the other aligned opening the said second mentioned pipe passing through said last mentioned bushing, coupling and pipe approximately to the end of the pipe and an inlet pipe for gaseous 100 fluid under pressure connected to the third side opening of the last mentioned bushing, a third pipe coupling materially larger than the others having a pipe secured at one end in one of its aligned openings and projecting 105 therefrom and a bushing in the other aligned opening through which the last two previously mentioned pipes pass into the end of the last mentioned pipe and an air supply pipe connected to the third side opening of 110 said last mentioned bushing.

10. A burner of the type described comprising in combination, a pipe coupling having a pipe of uniform interior diameter secured at one end in one of its two aligned 115 openings and extending a material distance therefrom, a bushing in the opposite opening of said coupling, a pipe having a uniform interior diameter less than that of the first pipe extending through said bushing 120 concentrically into the end of said first pipe, an inlet pipe for liquid fuel connected to the third side opening of said coupling, a second larger pipe coupling having a pipe of uniform diameter secured in and projecting 125 from one of its aligned openings and a bushing in the other aligned opening the said second mentioned pipe passing through said last mentioned bushing, coupling and pipe approximately to the end of the pipe and 130

an inlet pipe for gaseous fluid under pressure connected to the third side opening of the last mentioned bushing, a third pipe coupling materially larger than the others having a pipe of uniform diameter secured at one end in one of its aligned openings and projecting therefrom and a bushing in the other aligned opening through which the

last two previously mentioned pipes pass into the end of the last mentioned pipe and an air supply pipe connected to the third side opening of said last mentioned bushing.

10 In testimony whereof I hereunto affix my signature.

WALTER H. MILLER.
